US00D448988B1

(12) **United States Design Patent** (10) Patent No.: **US D448,988 S**
(45) Date of Patent: ** Oct. 9, 2001

(54) **STAND-UP POUCH FOR HOLDING LIQUIDS**

(75) Inventors: **Gary M. Bell**, Crystal; **Bobby Hira**, Bloomington, both of MN (US)

(73) Assignee: **Kapak Corporation**, Minneapolis, MN (US)

(**) Term: **14 Years**

(21) Appl. No.: **29/136,872**

(22) Filed: **Feb. 8, 2001**

(51) LOC (7) Cl. **09-05**

(52) U.S. Cl. **D9/305**

(58) Field of Search D9/305, 306; 222/92, 222/105, 107, 206, 215; 383/36, 61, 96, 97, 104, 106, 122

(57) **CLAIM**

The ornamental design for stand-up pouch for holding liquids, as shown and described.

DESCRIPTION

FIG. 1 is a perspective view of a stand-up pouch for holding liquids embodying our new design;

FIG. 2 is a reduced front view thereof;

FIG. 3 is a reduced rear view thereof;

FIG. 4 is a reduced right side elevational view thereof;

FIG. 5 is a reduced left side elevational view thereof;

FIG. 6 is a reduced top plan view thereof;

FIG. 7 is a reduced bottom plan view thereof;

FIG. 8 is a perspective view of a second embodiment of a stand-up pouch for holding liquids embodying our new design, the portions shown in broken lines forming no part of the design sought to be patented;

FIG. 9 is a reduced front view of the embodiment depicted in FIG. 8, the portions shown in broken lines forming no part of the design sought to be patented;

FIG. 10 is a reduced rear view of the embodiment depicted in FIG. 8, the portions shown in broken lines forming no part of the design sought to be patented;

FIG. 11 is a reduced right side elevational view of the embodiment depicted in FIG. 8, the portions shown in broken lines forming no part of the design sought to be patented;

FIG. 12 is a reduced left side elevational view of the embodiment shown in FIG. 8, the portions shown in broken lines forming no part of the design sought to be patented; and,

FIG. 13 is a reduced top plan view of the embodiment depicted in FIG. 8, the portions shown in broken lines forming no part of the design sought to be patented; the bottom plan view having the same appearance as that shown in FIG. 7.
